UNITED STATES PATENT OFFICE.

FRIEND W. SMITH, OF BRIDGEPORT, CONNECTICUT.

DESIGN FOR A TOY BANK.

Specification forming part of Design No. 6,744, dated July 1, 1873; application filed June 20, 1873.

To all whom it may concern:

Be it known that I, FRIEND W. SMITH, of Bridgeport, in the county of Fairfield and in the State of Connecticut, have invented certain new and useful Design for Toy Banks and Money-Boxes; and do hereby declare that the following is a full, clear, and exact description thereof, reference being had to the accompanying drawings and to the letters of reference marked thereon, making a part of this specification.

The nature of my invention is fully represented in the accompanying photographic illustration, to which reference is made.

The illustration represents a toy bank made egg-shaped, and provided with an opening for the deposit of money. The words "My nest-egg" are suitably printed, stamped, or placed thereon.

What I claim is—

The design for a toy bank, as herein shown and set forth.

In testimony that I claim the foregoing I have hereunto set my hand this 29th day of May, 1873.

Witnesses: FRIEND W. SMITH,
CURTIS THOMPSON,
SEYMOUR WHITING.
